UNITED STATES PATENT OFFICE.

ERNEST H. BAXTER, OF CHICAGO, ILLINOIS.

FUSE-PLUG.

1,379,436.

Specification of Letters Patent. Patented May 24, 1921.

Application filed November 10, 1919. Serial No. 336,910.

To all whom it may concern:

Be it known that I, ERNEST H. BAXTER, a citizen of the United States, residing at Chicago, in the county of Cook and State of Illinois, have invented a certain new and useful Improvement in Fuse-Plugs, of which the following is a full, clear, concise, and exact description, reference being had to the accompanying drawings, forming a part of this specification.

My invention relates to fuse plugs and more particularly to a fuse plug in which the fuse element may be renewed after being burned out.

15 In most of the lighting circuits in use at the present day and in many of the smaller electric circuits fuse plugs are used which have the general form of the screw plug on the ordinary electric lamp bulb. These 20 plugs are screwed into a socket having electrical connections like those of an ordinary lamp socket. The fuse contained with the plug is adapted to conduct a certain amount of current without melting. If the current 25 exceeds the amount for which the fuse is intended the fuse burns out and a new plug must be inserted. The fuse itself forms only a small portion of the fuse plug but the entire plug must, at the present time, be 30 thrown away because the plug is not so constructed that an amateur or a person unskilled in the electrical art can re-insert a new fuse. Throwing away the entire plug when only the fuse is destroyed entails a 35 great loss. It is an object of this invention to avoid this loss by providing a fuse plug having means whereby a new fuse may be inserted by any person not skilled in the art and without the use of any but ordinary implements. It is a further object of the 40 invention to provide a fuse plug of the character set forth which is inexpensive to manufacture, serviceable in use and is fire-proof as is necessary in plugs of this kind.

45 It is a further object to provide a fuse with the amperage plainly marked thereon so that a wrong fuse will not be selected and to provide a fuse which cannot be improperly placed in the plug.

50 It is a further object of the invention to provide a fuse plug in which the usual glass or izinglass cover plate may be removed so that access may be had to the interior of the plug for re-inserting a new fuse.

55 It is a further object of this invention to provide a fuse element adapted to be in-

serted into my improved plug which fuse element can be constructed more easily and manufactured more cheaply than the corresponding element shown in my copending 60 application Serial No. 333,749, filed Oct. 27, 1919. With these and other objects in view it will be apparent from the detailed description which follows I have disclosed in the drawings several forms which my invention 65 may take which forms are the best known to me at the present time. However, it is to be understood that by this specification and the accompanying drawings I do not intend to limit myself to the specific construction disclosed but intend to avail myself of any modifications which fall within the scope of the claims appended to this specification.

70 In the drawings the same reference characters have been used to designate the same parts throughout the several views. In these drawings—

75 Figure 1 is a central section taken through my improved fuse plug on approximately 80 line 1—1 of Fig. 3;

Fig. 2 is a transverse section through the end of the plug taken approximately on line 2—2 of Fig. 1;

Fig. 3 is an end view of the plug viewed 85 from the end shown at the bottom of Fig. 1;

Fig. 4 shows the fuse positioned in the clamping member preparatory to being secured to the body of the plug;

Fig. 5 shows a modified form of clamping 90 member. In this view a portion of the plug body is shown in section in order to more clearly disclose the co-operation between the parts;

Fig. 6 shows another modification of the 95 clamping member; and

Fig. 7 is a perspective view of the contact member to which the lower end of the fuse is attached.

100 My improved plug comprises a body member 10 which may be made of porcelain as is customary in fuse plugs of this character or may be made of any other desired material which has the necessary and required insulating properties. This body member 105 is shaped substantially as shown in Fig. 1 and has the usual hollow interior 11. The body member is provided with an enlarged portion 12 which is provided on its exterior surface with threads 13 which are adapted 110 to be engaged by corresponding threads on a cap member 14. The cap is provided with

an inwardly turned annular shoulder 15 which is adapted to engage the usual insulating or other transparent cover member 16 to clamp the same against the enlarged portion 12 of the body member. Beneath the enlarged portion 12 the body 10 is provided with exterior threads 17 which are adapted to be engaged by corresponding threads on a metal sleeve 18 which when turned completely onto the body member 10 assumes approximately the position shown in Fig. 1 of the drawings.

In one side of the body member 10 is formed a recess 19 which extends across the threads 17 and into an opening 20 which extends completely through the body member as shown in Fig. 1. The bottom of the recess 19 is shaped as shown in Fig. 1 so that it may accommodate the fuse clamping member which will now be described.

The clamping member 21 shown in Fig. 4 is substantially U-shaped. One of its legs is provided with an inwardly bent portion 22 and the other leg is provided with an outwardly curved portion 23. These portions are in alignment and are so positioned that the portion 22 fits into the portion 23 when the legs of the member 21 are collapsed by the sleeve 18. The member 21 is also provided with a finger 24 which is bent substantially at right angles to the leg of the member on which it is formed and this finger is adapted to fit into a suitable depression in the recess 19 as will be clear from Fig. 1. The recess 19 is also provided with a second depression which is adapted to accommodate the curved portion 23 of the clamping member.

My improved fuse 25 has a widened lower end 26 and a widened upper end 27 which is adapted to be positioned between the legs of the U-shaped member 21 and when so positioned extends below the curved portions 22 and 23.

The lower end of the fuse 25 is adapted to be positioned within a contact member 28 which is shown on large scale in Fig. 7 of the drawings. The contact member 28 is stamped from any suitable material and is made substantially in the form of a rifle cartridge and has an extending flange 29 which will fit against the end of the body member 10 as shown in Figs. 1 and 3. The contact member has its open end squared as shown at 30 and one wall of its squared portion is slotted as shown at 31 in Fig. 7 in order to provide a spring tongue 32. This tongue is provided with an engaging shoulder 33 which may be conveniently bent from the tongue 32 as shown in Fig. 7. After the end 26 of the fuse is positioned within the squared portion 30 of the contact member the member is filled with solder 34 in order to securely hold the end of the fuse in the contact member. The end of the body mem-

ber 10 is provided with a hole or opening 35 shaped to conform to the outside shape of the contact member 28. The contact member is long enough so that when it is pushed through the hole 35 the shoulder 33 will project above the edge of the opening on the inside of the body member 10. The tongue is resilient and permits the contact member 28 to be readily inserted into the hole or opening 35 but the shoulder 33 engages above the edge of the opening and prevents the member from falling out. It will be understood that the fuse 25 and the contact member 28 are assembled at the factory and are sold as a unit. The user will buy the complete fuse plug in the first instance only, thereafter when the fuse burns out he will merely purchase the fuse element which comprises the fuse 25 and the contact member 28, and will insert this fuse element into his former fuse plug.

The steps necessary in assembling are as follows: After the plug has burned out the operator will remove the sleeve 18 from the body 10 by unscrewing the same from the threads 17. This permits the clamping member 21 to be removed from the recess 19. The end 27 of the fuse which remains within the clamping member will be removed and thrown away. The fuse element will be inserted in the hole or opening 35 and pushed through the same until the shoulder 33 snaps above the edge of the opening. The end 27 of the fuse will be passed through the hole 20 and positioned between the legs of the clamping member, the members 14 and 16 being first removed to gain access to the interior of the plug. The sleeve 18 may then be replaced and as it is threaded onto the threads 17 will bend the legs of the clamping member together so that the end of the fuse will be bent to conform to the shape of the curved portions 22 and 23 as will be clear from Fig. 1 of the drawings. The members 16 and 14 are then replaced in position.

In Fig. 5 of the drawings I show a clamping member 36 which is shaped slightly different from the clamping member shown in Fig. 4. One leg of this clamping member has a portion of its leg bent as shown at 37 in Fig. 5 and the other leg has a portion bent as shown at 38 to correspond to the bent portion 37. The portion 38 fits into a depression 39 formed in the bottom of the recess 19 provided in one side of the body member 10. In this modification the end of the fuse does not extend below the bent portions 37 and 38 but extends only as far as shown in Fig. 5. When the sleeve 18 is threaded onto the body member 10 the portion 37 will bend the end of the fuse into the portion 38 and firmly secure the same.

In Fig. 6 I have shown a clamping member 40 which is substantially the same as

that shown in Fig. 4. This clamping member has an inwardly bent portion 41 and a coöperating outwardly bent portion 42. Above the portion 42 is a curved extension 5 43 which extends up over the shoulder 44 formed at the bottom of the opening 20 in the body member 10. This clamping member is so formed that its legs bear against each other as shown in Fig. 6. When the 10 fuse is to be inserted the legs must be bent outwardly by means of the fingers or any other convenient implement so that the end of the fuse may be positioned between them. When the sleeve is threaded onto the body 15 it will compress the clamping member and bend the fuse between the legs of the clamping member as shown in Fig. 1.

From what has been described it will be apparent that I have provided a fuse plug 20 which is simple to construct and in which the fuse may be easily replaced. I have avoided the use of all expensive threaded screws or member for securing the fuse in place within the plug. The contact member 25 22 can be formed out of the required metal stamped to substantially the shape shown in Fig. 7. The clamping member is made of any desired metal and has electrical contact with the sleeve 18.

30 The hole or opening 35 is square as shown in Fig. 2 and the squared end 30 of the contact member 28 snugly fits the opening. This prevents improper placing of the fuse in the plug as any operator would know 35 that one flat side of the fuse 25 should be directed toward the recess 19. Therefore, if the fuse is brought anywhere close to this position the squared opening will insure the proper positioning of the fuse. The end 40 of the contact member has stamped thereon the amperage of the fuse so that the wrong fuse will not be selected. This is clearly shown in Fig. 3.

With the modification shown in Fig. 5 it 45 will be practically impossible to break the fuse or tear it loose from the contact member 28 while it is being inserted. The portion 37 slightly overhangs the portion 38 so that the portion 38 presents a flat upper 50 surface against which the end of the fuse will contact when it is positioned in the clamping member 36. The length of the fuse is such that when its end contacts with the portion 38 there is enough slack in the 55 fuse to prevent tension being placed on the fuse when the clamping member 36 is collapsed by the ring 18. The fuse will therefore not be broken or torn away from the contact member 28.

60 Having thus described my invention what I claim as new and desire to secure by United States Letters Patent is:

1. A fuse plug of the character described comprising a body member, a removable 65 cover therefor, a screw threaded sleeve on

said body member, and means to clamp a fuse mounted between said sleeve and said body member.

2. A renewable fuse plug comprising a body member, a removable cover therefor, 70 a sleeve positioned on said body member, and a clamping member positioned between said body member and said sleeve and receiving one end of a fuse element.

3. A renewable fuse plug comprising a 75 body member having a recess in one of its sides, a sleeve positioned on said body member and covering said recess, and a clamping member positioned within said recess and held in closed position by said sleeve. 80

4. A renewable fuse plug of the character described comprising a body member, an opening formed in one end thereof, a recess formed in one side of said body member, a contact element removably positioned in 85 said opening, a clamping member positioned in said recess, a fuse connecting said contact member to said clamping member, and a sleeve positioned on said body member for securing said clamping member in 90 said recess.

5. A fuse plug of the character described comprising a body member having an opening in one end and a recess in its side wall, a contact member positioned in said opening and having a locking element adapted to lock the member in said opening, a fuse clamping member positioned within said recess, a fuse having one of its ends secured to said contact member and its other end 95 detachably held by said clamping member, and a sleeve positioned on said body member for holding said clamping member in clamping position.

6. A clamping member for a renewable 105 fuse plug comprising a substantially U-shaped strip of metal providing legs which are adapted to receive one end of a fuse between them, said legs having curved portions which coact to provide a bend in the 110 fuse between them.

7. A renewable fuse plug comprising a body member having a squared opening in one of its ends, a contact member having a squared body portion positioned within and 115 fitting said opening, and a locking tongue on said contact member for securing it within said opening.

8. A renewable fuse plug of the character described comprising a body member 120 having a squared opening in one end, a contact member having a squared body portion adapted to fit said opening, a locking element on said contact member to detachably secure the contact member within said opening, a fuse having one of its ends secured to said contact member, and a clamping member positioned exteriorly of said body member and receiving the other end of the fuse. 125

9. A renewable fuse plug comprising a body member having a squared opening on one end and a recess in one of its sides, a squared contact member positioned within 5 and fitting said opening, a spring tongue on said contact member for holding it in said opening, a clamping member within said recess, a fuse having one of its ends secured to the contact member and its 10 other end positioned within said clamping member, and a sleeve positioned on said body member for holding said clamping member in fuse clamping position.
10. A renewable fuse plug comprising a 15 body member having a recess in its exterior surface, and an opening extending through said body member, a clamping member positioned within said recess and receiving one end of the fuse which projects through 20 said opening, and a sleeve positioned on said body member and holding said clamping member in fuse clamping position.
11. A device of the character described 25 comprising a body member having exterior threads, a recess formed in said body member and extending across said threads, a fuse clamping member having legs adapted to receive a fuse between them, a sleeve engaging said threads and adapted when 30 turned onto said threads to compress said legs to clamp the fuse securely between them.
12. A device of the character described 35 comprising a body member having a squared opening in one of its ends, a contact member having a fuse secured thereto and being squared to fit said squared opening so as to facilitate the proper placing of the fuse within said body member.
13. A device of the character described 40 comprising a body member having an opening in one of its ends, a contact member positioned within said opening, a fuse having one of its ends secured to said contact member, a clamping member on said body member for holding the other end of the fuse, and means for retaining said clamping member in its clamping position, said clamping member being so formed as to prevent the fuse from entering too far into the clamp- 45 50 ing member.
14. A device of the character described comprising a body member having an opening in its end and a recess in its side wall, a fuse element extending through said opening and to said recess, a clamping member in said recess for holding the free end of said fuse element, said clamping member having means to properly position the free 55 end of the fuse element.
15. A device of the character described comprising a body member having exterior threads, a recess formed in said body member and extending across said threads, a fuse clamping member having legs adapted 60 65 to receive a fuse between them, the legs of said clamping member having offsets therein to form a bend in a fuse clamped between them, and a sleeve engaging said threads and adapted when turned onto said 70 threads to compress said legs to clamp the fuse securely between them.

In witness whereof I hereunto subscribe my name this 5th day of November A. D. 1919.

ERNEST H. BAXTER.
